William Danziger and Victor Achison,
New York, N. Y.

Application April 29, 1953, Serial No. 24,755

Term of patent 3½ years

(CL. D80—11)

To all whom it may concern:

Be it known that we, William Danziger and Victor Achison, both citizens of the United States, both residing at New York, in the county of New York and State of New York, have invented a new, original, and ornamental Design for a Display Advertising Device, of which the following is a specification, reference being had to the accompanying drawings, forming part thereof.

In the drawings:

Fig. 1 is a front perspective view of a display advertising device, showing our new design;

Fig. 2 is a front elevational view of the same; and

Fig. 3 is a side elevational view of the display advertising device.

We claim:

The ornamental design for a display advertising device, as shown.

WILLIAM DANZIGER.
VICTOR ACHISON.
